UNITED STATES PATENT OFFICE.

ANTON VELTING, OF MASPETH, NEW YORK.

METHOD AND APPARATUS FOR MAKING LAMP FILAMENTS.

Application filed October 31, 1923. Serial No. 671,850.

To all whom it may concern:

Be it known that I, ANTON VELTING, a native and citizen of Germany, and a resident of Maspeth, Long Island, county of 5 Queens, and State of New York, have invented certain new and useful Improvements in Methods and Apparatus for Making Lamp Filaments, of which the following is a specification sufficient to enable those 10 skilled in the art to which the invention appertains to utilize the same.

The object of my invention is to simplify and cheapen the production of the spirally convoluted light filaments used in incandescent electric lamps, and at the same time 15 render the product more perfect and uniform than previously attainable; and the invention consists essentially in forming said spiral convolutions of the filaments continuously on a fixed mandrel by and between 20 rotary dies having peripheral pitch threads relatively co-related, substantially as hereinafter described and claimed specifically,— in contradistinction to the old method of 25 forming the filament convolutions around a movable wire mandrel which has to be eliminated by chemical action, involving loss in both material time and labor.

In the accompanying drawings, I illustrate by way of exemplification apparatus adapted to the practical utilization of my invention, although I do not limit myself to the identical form and construction of parts shown, since modifications in minor details, 35 and equivalent mechanical expedients, may be resorted to with like results, and without departing from the spirit and intent of my invention in this respect.

Furthermore, the drawings are necessarily 40 made on a relatively large scale, approximately in the proportion of five to one as related to the actual size of apparatus,— the convoluted spiral filament product being in practice only about the diameter of twenty-five one-thousandths of an inch, more or 45 less.

With this understanding:

Figure 1 represents an elevation of the supporting frame and operative parts of 50 my filament spiralling means;

Fig. 2, a horizontal section thereof, taken upon plane of line 2—2 Fig. 1;

Fig. 3, a horizontal section thereof, taken upon plane of line 3—3 Fig. 1;

Fig. 4, a vertical sectional elevation taken upon plane of line 4—4 Fig. 2;

Fig. 5, an enlarged sectional view of the peripherally threaded formative dies only, but taken upon general plane of line 5—5 Fig. 1;

Fig. 6 is a sectional elevation of said formative dies, on the same scale as Fig. 5, illustrating the practical operation thereof in conjunction with said Fig. 5,—the grooves in the periphery of the die shown 65 in elevation being omitted in part for clearness of illustration;

Fig. 7 is a detail view of the fixed mandrel member;

Fig. 8 is a detail view of one of the formative die shafts, broken away in part;

Fig. 9 is a detail elevation, broken away in part, of the power shaft; and

Fig. 10 is a detail elevation, broken away in part, of the intermediate power trans- 75

In the specific construction of apparatus shown in the drawings, B, represents what may be designated as the base plate, and B', the head plate, both united integrally 80 and fixedly supported as related to each other by standard-bolts b, b, which latter, with said base and head plates B, B', constitute the rigid frame work upon and within which the operative parts are mounted. 85

M, is a fixed mandrel rigidly attached to the head plate B', and extending downward therefrom in an axial line central as related to the three equi-distant formative dies d', d², d³, each integral with its own shaft D', 90 D², D³,—all three shafts being rotatably mounted between the base plate B, and the head plate B', and each being also formed integrally with its own pinion d^x, near its lower extremity.

These pinions d^x, mesh with, and are driven by, gears p, and i, the one p, on the power shaft P, and the other i, on the intermediate shaft I, as indicated more particularly in Fig. 3, of the drawings,—said shafts 100 P, and I, being rotatably mounted upon and between the base plate B, and the head plate B'.

The formative dies, d', d², d³, are shaped peripherally with spiral grooves or threads 105 of like depth and pitch, but so timed and positioned as related to each other as to constitute between them a spiral matrix for the creation of the desired convolutions c, of the wire w, used subsequently in the formation of the usual filament loops for installation in the glass bulbs of incandescent lamps 110

in a manner well known in the art,—my invention relating solely to the means and method of forming the usual convolutions on said filament wire.

5 By my invention I attain a perfect, positive product, in a simple, cheap and effective manner, there being practically no waste of material involved, with a minimum of time and labor, obviating the loss incidental to, 10 and inevitable in, the old method of forming the filament convolutions around a soluble wire mandrel, subsequently removed by chemical action.

It is to be understood that the formative dies d' , d^2 , d^3 , are of equal diameter, and that the pinions d^x , are also of equal diameter.

What I claim as my invention and desire to secure by Letters Patent is:

20 1. The method herein set forth of convoluting filaments for incandescent electric lamps of the character designated, consisting in passing the filament wire over a fixed mandrel and between a plurality of formative dies having peripheral thread-grooves of like pitch and depth and relatively positioned to afford a spiral matrix by and between their opposed surfaces and said fixed mandrel, holding said mandrel fixed during 25 such operation and removing the completed filament from the mandrel, substantially in the manner and for the purpose set forth.

2. Apparatus for convoluting filaments for incandescent lamps of the character 30 designated, comprising a fixed mandrel in-

dependent of the completed filament, and a plurality of formative dies each with its own pinion and having peripheral thread-grooves of like pitch and depth and relatively positioned to afford a spiral matrix 40 by and between their opposed surfaces and said fixed mandrel, substantially in the manner and for the purpose set forth.

3. Apparatus for convoluting filaments for incandescent lamps of the character 45 designated, comprising a fixed mandrel independent of the completed filament, and three equidistant formative dies each with its own pinion and having peripheral thread-grooves of like pitch and depth and 50 relatively positioned to afford a spiral matrix by and between their opposed surfaces and said fixed mandrel, substantially in the manner and for the purpose set forth.

4. In a device of the character stated, a 55 base plate, a head plate, means holding them at a predetermined distance apart, a mandrel rigidly affixed in the head plate, equidistant formative dies about said mandrel and in axial alignment centrally therewith, shafts 60 integral with said dies, means for rotating said shafts, pinions on said shafts, and gears for actuating said pinions, said dies forming a spiral matrix for forming convolutions of a wire.

ANTON VELTING.
